UNITED STATES PATENT OFFICE.

MARTINUS SIEVEKING, OF STATEN ISLAND, NEW YORK, ASSIGNOR TO FLYING EAGLE COMPANY, INC., A CORPORATION OF NEW YORK.

MOBILE FIGURE.

1,419,694.

Specification of Letters Patent. Patented June 13, 1922.

Application filed April 13, 1921. Serial No. 461,026.

To all whom it may concern:

Be it known that I, MARTINUS SIEVEKING, a citizen of Holland, and a resident of Staten Island, in the county of Richmond and State 5 of New York, have invented certain new and useful Improvements in Mobile Figures, of which the following is a specification.

This invention has reference to devices that form an ornament for suitable locations especially a figure attachment for motor vehicles to be placed on the radiator cap or similar place at the front of the car; and which figure is provided with movable parts, such as wings, that are caused to vibrate or flap to simulate 15 the flying of a bird, and which are put in motion principally by the jarring of the vehicle.

The object of the present invention is to provide an improved figure device of this 20 character that will be operated by actuating means, when the wing-like members are swung by the jarring of the car; which actuating means are effective to retain the wings normally in a certain position of rest, 25 and when the wings are swung from this position, such means will return the wings by a synchronous movement to the rest position, preferably through a number of oscillations in unison about the rest position.

30 In the accompanying drawing showing one embodiment of my invention, Figure 1 is a perspective view of the device, attached to a radiator cap.

Fig. 2 shows separately the spring and 35 means connecting it with the wings.

Fig. 3 is a vertical cross-section at the middle portion.

A construction of a similar kind is set forth in U. S. patent granted to me, November 18, 1919, No. 1,322,364. In the construction therein set forth, the wing-like members are shown controlled by a gravity influenced member, in the form of a weight, connected with the wings by links and levers. In the present construction, the controlling or operating means is in the form of a resilient member, such as a spring plate; and the wings are operably connected with the spring, to swing in unison.

50 As set forth, I provide a figure or body in the form of a bird, denoted generally by 2. On each side are wings 3 and 4, each mounted to oscillate on a substantially horizontal axis, extending longitudinal to the body on 55 each side. As shown, the wing 3 is secured

to a rod, that hinges or rocks in ears 5 and 6, bent outwardly from the body member 2, which may be formed of sheet metal. The bar 4' is bent at one end 7, and secured to the wing 3 to cause the bar to swing with the wing in the hinge ears. This bar 4' has an end portion 8 extending into the body with another bent portion 9, extending rearward. The other wing 4 has a similar bar 10 with a flat portion 1 secured to the wing. This bar is bent at 11 and at 12, to extend rearwardly, opposite the bent portion 9 of the other bar.

A suitable spring is provided inside of the body, such as a plate spring 15, that has one part secured to the body, with the front end free to oscillate, and which engages the bent ends of the wing rods 4' and 10. As shown, I provide a wire loop member 13 having portions in the nature of slots extending laterally, into which projects the bent ends 9 and 12, of the wing rods, this loop member being secured by a bolt 14 to the spring 15; which spring is secured by a bolt 16 to the upper wall of the body, as shown in Fig. 3. 80

The wings 3 and 4 hinged at their inner ends to the body, tend to swing downward on the hinge rods carried by the wings, which rods extend into the loop on the plate spring, and serve to hold the wings in a normal position of rest, substantially horizontal. It will be readily understood that the jarring of the vehicle will tend to vibrate the wings or swing them downward, and this will increase the tension on the plate spring. The latter will thus be energized, and will react to swing the wings back to their normal horizontal position. But the latter movement would naturally have a tendency to swing the wings up beyond the position of rest, by the reaction of the tensioned spring, and then a slight tension would be put in the spring plate to swing the wings downward again. This will occur a number of times and the wings are thereby oscillated, in unison, the greater the initial movement of the wings, the greater the amplitude of the vibration and the greater the number of times they will oscillate, in synchronism. 100

It will be seen that the controlling rods 105 are rigidly secured to each wing, and that these rods engage a slotted link that is rigidly attached to the plate spring. Therefore a single rigidly attached resilient controlling member movably engages each wing 110

member, and no intermediate parts are used. This tends to simplicity and economy in construction, and also enhances the durability of the device.

5 The device may be provided with suitable means for securing it to a radiator cap or the radiator tube below the cap on a motor vehicle. As shown I make use of the flat plate spring 15, that is extended rearward 10 and secured to the body by a second bolt 17 and projects beyond the body, as shown in Fig. 1 with its end portion bent downwardly, and suitably secured to a clamping band 18 having a bolt 19 at the rear to secure it to the 15 radiator tube as shown.

It will be seen from the description that the device provides wing members that are so connected by the operating mechanism that they necessarily swing in unison, that is 20 if one wing swings upward the other wing must swing upward the same amount and to the same relative position, and also if swung downwardly they must swing in unison.

This is independent of the spring itself, 25 that has connecting mechanism that forces one wing to swing exactly the same as the other wing, which is precisely similar to the flight of a bird whose wings always flap in unison. It will thus be understood that I 30 have provided an actuating member that when the wings, or either of them is swung beyond the rest position, in either direction, energizes the actuating member, that is thereby caused to oscillate the wings in unison 35 back to the rest position. It will be further observed that the wings are arranged substantially horizontal and thereby are not influenced by the forward movement of the car or by wind pressure generally, the means for 40 supporting the figure or body comprising an extension of the plate spring 15, will insure a considerable amount of vibratile movement of the body with resultant vibration of the wings; but it is to be understood that the 45 mounting of the body on the radiator cap or other part of a motor vehicle would necessarily result in very considerable vibration being imparted to the body in a vertical direction, and that the device is operative 50 without the employment of the spring support.

What I claim is:

1. A figure of the character set forth, comprising a body member, means for mounting 55 the body to effect vertical vibratile move-

ment thereof, a pair of wing-like members vibratably mounted substantially horizontal on each side of the body and movable under the influence of vibrations of the body, an arm on each said wing member projecting inwardly, a spring secured to and within the body with one end free and operably engaging both said arms to retain the wing members in a certain normal position of rest relative to the body, whereby when the 60 wing members are swung beyond said rest position in either direction by vertical movement of the body, said spring becomes tensioned to react and return the wing members by a synchronous movement to the said rest 65 position.

2. A figure of the character set forth, comprising a body, means for mounting said body to effect vertical vibratile movement thereof, a pair of wing-like members vibratably mounted substantially horizontal on each side of the body, an arm fast on each wing member projecting inwardly with the end bent transversely, a flat spring secured in the body member, a slotted piece on the free end of the spring engaging both said bent arms to retain the wing members in a certain normal position of rest relative to the body, whereby when the wing members are swung beyond said rest position in either direction by vertical movement of the body, said spring becomes tensioned to react and return the wing members by a synchronous movement to the said rest 75 position.

3. A figure of the character set forth, comprising a body, a pair of wing-like members vibratably mounted substantially horizontal on each side of the body, an arm on each said member projecting inwardly, a spring secured in the body with one end free and operably engaging both said arms to retain the wing members in a certain normal position of rest relative to the body, whereby when the wing members are swung beyond said rest position in either direction by vertical movement of the body, said spring becomes tensioned to react and return the wing members by a synchronous movement to the said position, said spring plate being extended rearward beyond the body, and a 80 clamping member on the rear end of the spring plate.

Signed at New York city, N. Y., on April 11, 1921.

MARTINUS SIEVEKING.
